J. C. SHELLER

ATTACHABLE SHOWER

Filed Aug. 19, 1927

UNITED STATES PATENT OFFICE.

JOHN C. SHELTER, OF MAYWOOD, ILLINOIS, ASSIGNOR TO JOHN F. SAYE, OF MAYWOOD, ILLINOIS.

ATTACHABLE SHOWER.

Application filed August 19, 1927. Serial No. 214,149.

My invention relates to improvements in attachable showers, and it consists in the combinations, constructions, and arrangements herein described and claimed.

5 An object of my invention is to provide a device of the type described which may be readily secured to a bath tub and which has novel means for preventing the water from getting on the floor and for guiding the water 10 into the bath tub.

15 A further object of my invention is to provide a device of the type described which may be attached to the bath tub without the assistance of a plumber, thus rendering the device simple in construction, durable, and efficient for the purpose intended.

20 Other objects and advantages will appear in the following specification, and the novel features of the invention will be particularly pointed out in the appended claims.

25 My invention is illustrated in the accompanying drawings, forming part of this application, in which

Figure 1 is a side elevation of my device 25 as applied to a bath tub,

Figure 2 is a section along the line 2--2 of Figure 1,

Figure 3 is a section along the line 3--3 of Figure 1, and

30 Figure 4 is a section substantially along the line 4--4 of Figure 2.

In carrying out my invention, I provide a frame, indicated generally at 1, and formed of sections 2, 3, 4, 5, 6 and 7. These sections 35 are provided with arcuate shaped under surfaces 8 which conform to the top of a bath tub indicated at 9. The sections are provided with integral walls 10 which curve inwardly for a purpose hereinafter described.

40 The sections are provided at their extremities with integral flanges 11 through which bolts or rivets 12 are disposed for securing the sections of the frame together. The sections 2, 4, 5 and 7 are provided with inwardly 45 extending integral retaining lugs 13 at their innermost ends which are arranged to extend beneath the top of the bath tub 9, see Figure 3. The sections 2, 4, 5 and 7 are also provided with integral receiving portions

50 14 for receiving uprights 15. The sections 3 and 6 are provided with longitudinally extending rods or bars 3' and 6' for receiving the ordinary type of bath tub seat. A tubu-

lar curtain frame 16 is secured to the uprights 15 by means of T connections 17. 55

A curtain 18 is adjustably secured to the tubular frame 16 by means of rings 19 which are secured to the upper edge of the curtain. The lower edge of the curtain 18 extends around the frame 1 upon the inside thereof 60 and is secured to the wall 10 by any suitable means, such as stitches 20.

65 A top spray 21 is positioned as shown in Figure 4 and is in communication with water supply pipes 22 through a pipe 23 which is held by the tubular frame 16 at 24. The connection 24 provides communication between the water feed pipes and the tubular frame 16. End sprays 25 and 26 are secured to the tubular frame 16 by T connections 27 70 and 24.

75 From the foregoing description of the various parts of the device, the operation thereof may be readily understood. The curtain may be moved to one side where the ends thereof meet, as indicated at 28, for allowing the user to enter the tub. The water is turned on in the usual way and, due to the connection therewith, the water is permitted to pass from the top spray 21 and from the end sprays 80 25 and 26 through the tubular frame. The purpose of the curtain 18 is to prevent the splashing of the water upon the walls or floor of the bath room. The special construction of the curtain and the frame 1 prevents any 85 possibility of the water getting upon the floor.

By viewing Figures 3 and 4, it will be noted that the curtain is drawn inwardly from the upper extremity thereof, and, as it engages with the walls 10 of the frame 1, it tapers inwardly toward the inside of the bath tub 9. In this manner, all water which contacts with the screen 18 is guided into the bath tub. This is the main purpose of the special curvature of the walls 10. The lugs 95 13, as they extend beneath the top of the tub 9, hold the entire device against displacement.

I claim:

1. A device of the type described comprising a frame arranged to be secured to a bath 100 tub, uprights carried by said frame, a tube similar in general curvature to said frame, a downwardly extending spraying member, communications between said spraying member and said tube, a curtain adjustably carried 105 by said tube, an inwardly extending spraying

member carried by and in communication with said tube, and means integral with said frame for receiving a portion of said curtain for guiding water which engages with said curtain into the tub.

2. A device of the type described comprising a frame having center sections and end sections arranged to be disposed upon the upper edge of a bath tub, lugs carried by said sections for extending beneath the edge of said bath tub for anchoring the frame thereto, means for securing said sections together, and supporting bars carried by said center sections.
- 15 3. A device of the type described comprising a frame arranged to be disposed upon and extend completely around the upper edge of a bath tub, means for securing said frame to said bath tub, a tube similar in general contour to said frame, means carried by said frame for supporting said tube, sprays carried by and communicating with said tube, means for connecting said tube with a water supply, whereby water may pass through said tube and said sprays, an arcuate-shaped guide flange carried by said frame, and a curtain carried by said tube and having the lower ends thereof disposed adjacent and in contact with said flange, whereby water engaging with said curtain will be directed into the bath tub by the guide flange.
- 20

and means for connecting said tube with a water supply, whereby water may pass through said tube and said sprays. 25

4. A device of the type described comprising a frame arranged to be disposed upon and extend completely around the upper edge of a bath tub, means for securing said frame to said bath tub, a tube similar in general contour to said frame, means carried by said frame for supporting said tube, sprays carried by and communicating with said tube, means for connecting said tube with a water supply, whereby water may pass through said tube and said sprays, an arcuate-shaped guide flange carried by said frame, and a curtain carried by said tube and having the lower ends thereof disposed adjacent and in contact with said flange, whereby water engaging with said curtain will be directed into the bath tub by the guide flange. 30 35 40

JOHN C. SHELLER.
